[57] CLAIM

The ornamental design for a fiber-optic cable stripper,
as shown and described.

DESCRIPTION

FIG. 1 is a top, front and one side perspective view of
the fiber-optic cable stripper showing my new design;
FIG. 2 is an opposite side elevational view thereof; and
FIG. 3 is a bottom plan view thereof.

FIG. 4 is a rear elevational view thereof.

Portions of the claimed article in FIG. 1 are shown
separated for illustrative purposes only.

FIG. 1.

FIG. 2.

FIG. 3.

FIG. 4.
